UNITED STATES PATENT OFFICE.

HORATIO B. HOLLIFIELD, OF WASHINGTON, DISTRICT OF COLUMBIA.

PRACTICE APPARATUS FOR SMALL-ARMS.

1,130,403.

Specification of Letters Patent.

Patented Mar. 2, 1915.

Application filed October 30, 1914. Serial No. 869,834.

To all whom it may concern:

Be it known that I, HORATIO B. HOLLIFIELD, a citizen of the United States, residing at Washington, in the District of Columbia, have invented certain new and useful Improvements in Practice Apparatus for Small-Arms, of which the following is a specification, reference being had therein to the accompanying drawing.

This invention relates to practice apparatus for small arms, and particularly to the class of apparatus which involves the use of a pointed marking rod to be projected from the barrel, by the impact of the firing pin, to mark a miniature target and instantly retracted by a spring.

The object of this invention is to provide apparatus adapted for use in a rifle with additional devices whereby it may be accurately centered and held in a shot gun of any ordinary gage and length of barrel, whether or not the gun be choke bored.

In the accompanying drawings, Figure 1 shows in side view a gun provided with my devices. Fig. 2 shows in like view the common practice apparatus provided with my novel devices. Fig. 3 is a partial enlarged view showing in axial section the devices in the muzzle portion of a gun barrel. Fig. 4 is a section at 4-4, Fig. 3, looking toward the left.

In these figures, A represents a gun barrel, B the marking rod proper, C a tube enclosing the rod and fitting an ordinary rifle and D a spring within the tube, for retracting the rod, all being without novelty.

In order that the common apparatus may be accurately centered and held in any ordinary shot gun, or the like, it is provided with detachable devices for both its rear and forward portions, whereby it is accurately adjusted in the larger bore. These devices consist of springs E, E secured to the inner end of the tube and analogous springs F, F detachably and slidably fixed to the forward portion of said tube. The springs E, which are or may be very light since they merely hold the rear end of the tube in alinement, are shown as four in number, although three or more may be used, are simple bars curved outward centrally, free at one end and at the other fixed to a short sleeve E' which is threaded upon the inner end of the tube. The similar oppositely turned springs F are preferably heavier and are secured at one end to a sleeve F' which

slides upon the tube and is secured thereto by a setscrew G. Upon this setscrew is threaded a short sleeve I bearing an integral disk I' provided with a marginal cylindrical flange J which is externally milled and which gradually increases in width from a minimum on one side to a maximum on the opposite side, thus forming a sort of rotary wedge.

In assembling, the forward centering device is slipped upon the tube and the rear centering device is screwed into position, and the device I, J is so turned that the narrower side of the flange is toward the rear. The tube is then pushed into the barrel from the muzzle, the rear springs being compressed more or less according to the size of the bore, and the outer centering device is forced along the tube until the springs F are fully inserted in the barrel, when the device is locked to the tube by the setscrew G. Obviously, if the springs of each set be uniform, the tube's axis will accurately coincide with the axis of the barrel, whatever the bore of the latter, and as plainly the outer or forward centering device will occupy a position upon the tube depending upon the length of the particular barrel. Finally the wedge like flange is rotated until it gently presses upon the exterior of the barrel's muzzle portion, thereby giving additional security against accidental displacement of the devices in practising with the gun, and especially the slight rearward crawling of the tube, which leaves the rod relatively too far forward, and in case of use in a revolver, causes locking of the cylinder. This forward centering device also serves as a stop limiting the distance to which the tube may enter the barrel. For example, if dummy cartridges are used, the stop may be fixed to the tube at such point that the rod just reaches the point of the dummy cartridge, whatever its length, and thereafter no change need be made so long as like cartridges are used.

Obviously the devices added to the usual practice rod may be quickly removed when it is to be again used in a rifle.

What I claim is:

1. In a device of the class described, the combination with a practice rod tube, of two spring centering devices detachably secured to said tube near its ends, respectively, and each adapted for frictional engagement with the interior of gun barrels of different

internal diameters, the forward or outer device being arranged for adjustment longitudinally of the tube to bring it into the muzzle of a longer or shorter barrel in 5 which the tube may be inserted.

2. In a device of the class described, the combination with a practice rod tube, or members detachably secured to the rear and forward end portions of the tube, respectively, and each having a series of angularly spaced spring bars bent outwardly from the tube between their ends for frictionally engaging the interiors of barrels of different internal diameters, and means for locking 15 the forward member to the muzzle portion of a gun barrel.

3. In apparatus of the class described, the combination with a practice rod tube, of a radially compressible spring centering device 20 detachably fixed upon the inner end of the tube, and a second similar device adjust-

able along the tube, means for locking the second device to the barrel, and means always without the barrel in which the tube is used for locking the second device to the 25 tube.

4. The combination with a practice rod tube to be inserted in the barrel of small arms, of spring tube-centering devices 30 removably mounted on the end portions of the tube, respectively, means for locking the forward device to the tube, and means for clamping the said forward device to the muzzle of the barrel in which it may be inserted. 35

In testimony whereof I affix my signature in presence of two witnesses.

HORATIO B. HOLLIFIELD.

Witnesses:

ROBERT CRAIG GREENE,
SAMUEL M. BROSIUS.
